UNITED STATES PATENT OFFICE.

HENRY F. EBERT, OF WOODHAVEN, NEW YORK.

BRUSH.

Application filed July 15, 1926, Serial No. 122,668. Renewed December 1, 1928.

This invention relates to brushes and has special reference to the types of brushes wherein the bristles have their basal portions set into a ferrule and there held by a cement 5 preferably of rubber.

One important object of the invention is to improve the general construction of brushes of this character.

A second important object of the invention 10 is the provision of improved means for securing the bristles in the ferrule of such a brush.

A third important object of the invention 15 is to provide an improved locking element of novel construction for securing such bristles.

With the above and other objects in view as will be hereinafter apparent, the invention consists in general of certain novel 20 designs of construction and combinations of parts hereinafter fully described, illustrated in the accompanying drawings and specifically claimed.

In the accompanying drawings like characters of reference indicate like parts in the several views, and:

Figure 1 is a side elevation of the improved brush removed from its handle.

Figure 2 is an axial section therethrough. 30 Figure 3 is an end view of the ferrule used herewith.

Figure 4 is an enlarged perspective view of the locking element.

In the brush here shown there is provided 35 a ferrule 10 of cup shape and this ferrule has one end open and the other end provided with a closure 11 wherein is a polygonal opening 12 preferably triangular in form. Adjacent the open end there is provided 40 an annular flange 13 and the ferrule is also preferably formed with a screw thread 14 so that it may be screwed into the socket of a suitable handle (not shown).

The bristles 15 are bunched in the usual 45 manner and have their butts or basal ends positioned in the ferrule and there secured by a cement 16 of suitable rubber composition. The locking member is polygonal in cross section as at 17 to fit the opening 12, being accordingly preferably triangular in cross section. This member is slightly 50 longer than the ferrule and terminates at one end in a pyramidal point 18 and at the

other end in a flat disk shaped head 19 which bears against the outside surface of the 55 closed end of the ferrule. This member also has a series of spaced circumferential grooves 20. When this member is inserted the butts of the bristles are tightly compacted in the ferrule and the cement, entering the grooves 20, holds the locking member 60 firmly in position so that it cannot accidentally come loose. In fact the locking member is so securely held that it can only be withdrawn by destroying the brush and also 65 the bristles cannot come loose on account of the manner in which this member compacts them in the ferrule.

There has thus been provided a simple and efficient device of the kind described and 70 for the purpose specified.

Having thus described the invention, what is claimed as new, is:

1. A brush comprising a ferrule closed at one end and open at the other, a bunch of 75 bristles having their basal ends inserted in the ferrule and there secured by cement, and a headed locking member extending through the closed end of the ferrule and compacting the basal ends of the bristles within said ferrule, said locking member being polygonal in cross section and having a pyramidal point projecting into the bristles beyond the ferrule.

2. A brush comprising a ferrule having 85 one end closed and provided with a centrally disposed triangular opening, bristles having their basal ends positioned in the ferrule, a locking member of triangular cross section having a point at one end and a disk shaped 90 head at the other, said member passing through the opening in the ferrule and the head resting against the closed end of the ferrule, said member being further provided with spaced circumferential grooves, 95 and cement in said ferrule surrounding the bristles and member and entering said grooves.

3. A bristle locking element for brushes consisting of a polygonal body having a 100 pyramidal point at one end and a disk shaped head at the other end, said body having spaced circumferential grooves.

In testimony whereof I affix my signature.

HENRY F. EBERT.
